[57] CLAIM

The ornamental design for a bottle, as shown and described.

DESCRIPTION

FIG. 1 is a front elevational view of a bottle showing my new design;

FIG. 2 is a view looking from the left of FIG. 1, the opposite side being substantially a mirror image thereof;

FIG. 3 is a top plan view;

FIG. 4 is a bottom plan view;

FIG. 5 is a rear elevational view;

FIG. 6 is an exploded, fragmentary view showing the overcap removed from the body of the bottle;

FIG. 7 is a top plan view with the overcap removed from the body of the bottle;

FIG. 8 is a side view corresponding to FIG. 2 showing the overcap removed from the body of the bottle; and FIG. 9 is a central sectional view through the overcap and showing it removed from the body of the bottle.

FIG. 3

FIG. 1
